A. J. CULP

EXHAUST TRAP AND VALVE THEREFOR

Filed Oct. 27, 1927

UNITED STATES PATENT OFFICE.

ARTHUR J. CULP, OF CLANTON, ALABAMA.

EXHAUST TRAP AND VALVE THEREFOR.

Application filed October 27, 1927. Serial No. 229,133.

This invention relates to exhaust traps for hydrocarbon engines, and has for one of its objects to provide a novel and simple device of this character which shall be adapted to prevent any back pressure in the cylinders of the engine when the exhaust valves thereof are opened.

A further object of the invention is to provide an exhaust trap of the character stated which shall embody a valve associated with the discharge port and adapted to quickly open to permit a charge of gas to escape from the trap and adapted to quickly close to prevent air entering the trap.

15 A still further object of the invention is to provide an exhaust trap of the character stated which shall embody novel means for mounting the valve and novel means for yieldingly maintaining the valve seated.

20 With the foregoing and other objects in view, the nature of which will appear as the description proceeds, the invention consists of the construction, combination and arrangement of parts hereinafter fully described and claimed, and illustrated in the accompanying drawing, wherein:

Figure 1 is a sectional view taken on a vertical plane extending centrally and longitudinally through the exhaust trap.

25 Figure 2 is a sectional view taken on the vertical plane indicated by the line 2—2 of Figure 1.

Figure 3 is a sectional view taken on a horizontal plane indicated by the line 3—3 of Figure 2, and

30 Figure 4 is a sectional view taken on the vertical plane indicated by the line 4—4 of Figure 2.

The exhaust trap comprises a cylinder 1 which has its end wall 2 provided with an intake port 3 and its end wall 4 with a discharge port 5 and within which are arranged baffle plates 6. A pipe 7 extending from the exhaust manifold of a hydrocarbon engine, 35 not shown, enters the intake port 3. A gas-tight connection between the cylinder 1 and pipe 7 is established by a packing gland 8. The end wall 2 may be formed integrally with the side wall 9 of the cylinder 1, as 40 shown. The end wall 4 is made separately from the side wall 9, and it is secured by machine screws 10 to an annular flange 11 extending inwardly from the side walls. An asbestos gasket 12 is positioned between the 45 end wall 4 and the flange 11, and it is secured in place by the screws 10. The end wall 4

is provided in its outer side with a recess 13, and it is provided at opposite sides of the recess with outwardly directed flanges 14. A metal plate 15 which constitutes a valve seat, is secured within the recess 13 by certain of the screws 10, and is provided with an opening 16 registering with the discharge port 5. The flanges 14 are provided with slots 17 which extend in the direction of the axis of the cylinder 1 and which open out through the outer edges of the flanges. A valve 18 positioned between the flanges 14 and pivoted to the flanges by trunnions 19, is straight and flat and lies in full abutting contact with the seat 15 when closed. The trunnions 19 project laterally from flanges 20 on the valve 18 and are rotatably and slidably mounted in the slots 17. The flanges 20 extend outwardly from the valve 18, and they also extend beyond the pivoted end of the valve. The flanges 20 are connected by a bar 21, and are provided with inclined inner edges 22 in order to permit the valve 18 to be rocked into opened position. A U-shaped pressure bar 23 is positioned between the valve 18 and a yoke 24 secured to the end wall 4 by machine screws 25. The side members 26 of the pressure bar 23 are slidably mounted in the slots 17, and they are provided in their inner or free ends with recesses 27 for the reception of the trunnions 19. A leaf spring 28 which is secured to the cross member 29 of the pressure bar 23 by a machine screw 30, contacts 35 with the corresponding member 31 of the yoke 24. The side members 32 of the yoke 24 are positioned laterally beyond the flanges 14, and are provided with apertured lugs 33 for the reception of the screws 25.

A cap or housing 34 is provided for the valve 18 and the parts associated therewith. The cap 34 is secured in place by the screws 10, and an asbestos gasket 35 is positioned between the cap and end wall 4. The cap 100 34 is preferably of cylindrical formation, and is provided in its side wall with a circumferentially extending discharge port or slot 36.

In practice, the exhaust gases flow from 105 the cylinders of the engine to the cylinder 1 of the exhaust trap by way of the pipe 7. When the pressure in the cylinder 1 becomes greater than the power of the spring 28, the valve 15 opens and the gases enter 110 the cap 34 from which they pass by way of the port 36. As soon as the pressure in

the cylinder 1 becomes less than the power of the spring 28, the valve is again closed, with the result that air is excluded from the cylinder 1 and no back pressure occurs in the cylinders of the engine. During its initial opening movement, the valve 18 moves bodily outward, and during the remainder of its opening movement, the valve rocks on its trunnions 19 until the edges 22 of the flanges 20 contact with the valve seat 15. The bodily outward movement of the valve 18 tensions the spring 28 sufficiently to insure the rapid closing of the valve when the pressure in the cylinder 1 becomes less than the power of these springs.

The valve seat 15 is preferably made from soft copper. Due thereto and as the valve 18 closes flat against the seat 15, all air is excluded from the cylinder 1. The valve 18, 20 the pressure bar 23 and the yoke 24 may be easily and quickly assembled on the end wall 4 and may be easily and quickly removed therefrom when necessary to clean the valve and its seat 15. The valve seat 15 may also 25 be easily and quickly renewed, and as it is made of soft copper it prevents the chattering of the valve 18.

While the valve is shown and described in connection with a particular type of exhaust trap, which trap consists of the cylinder 1 and baffles 6, it is to be understood that the valve may be used in connection with any well known form of exhaust trap and particularly those shown in my U. S. Letters Patent 30 No. 1,514,441, granted Nov. 4, 1924, my application filed May 23, 1925, serially numbered 32,365, and allowed Sept. 17, 1927, and my application filed January 19, 1926, and serially numbered 82,312.

From the foregoing description, taken in connection with the accompanying drawing, the advantages of the construction and of the method of operation of the exhaust trap will be readily apparent to those skilled in the art to which the same appertains. While I have described the principle of operation of the exhaust trap, together with the structure which I now consider to be the best embodi- 40 45

ment thereof, I desire to have it understood that the structure shown is merely illustrative, and that such changes may be made when desired as are within the scope of the invention as claimed. 50

What is claimed is:—

1. In combination, a member provided with a port, flanges carried by the member at opposite sides of the port and provided with slots, a valve for the port and provided with trunnions slidably and rotatably positioned in the slots of the flanges, and means yieldingly holding the valve in closed position and preventing displacement of the trunnions from the slots. 55

2. In combination, a member provided with a port, flanges carried by the member at opposite sides of the port and provided with slots, a valve for the port and provided with trunnions slidably and rotatably mounted in the slots, a pressure bar slidably mounted in the slots and contacting with the trunnions, and means engaging the pressure bar to yieldingly hold the valve in closed position. 65 70

3. In combination, a member provided with a port, flanges carried by the member at opposite sides of the port and provided with slots, a valve for the port and provided with trunnions slidably and rotatably mounted in the slots, a yoke secured to the member, a pressure bar slidably mounted in the slots 75 80 and contacting with the trunnions, and a spring positioned between the pressure bar and yoke to hold the valve in closed position.

4. In combination, a member provided with a port, elements carried by the member at opposite sides of the port and provided with slots, a valve for the port provided with trunnions slidably and rotatably mounted in the slots, and means preventing displacement of the trunnions from the slots, said means including a yieldable element serving to normally hold the valve in closed position. 85 90

In testimony whereof I affix my signature.

ARTHUR J. CULP.
